UNITED STATES PATENT OFFICE.

RICHARD E. DILL, OF BELVIDERE, NEBRASKA.

PIT-SILO-WALL CONSTRUCTOR.

1,222,586.

Specification of Letters Patent.

Patented Apr. 10, 1917.

Application filed August 19, 1914, Serial No. 857,472. Renewed March 1, 1917. Serial No. 151,870.

To all whom it may concern:

Be it known that I, RICHARD E. DILL, a citizen of the United States, residing at Belvidere, in the county of Thayer and State of Nebraska, have invented certain new and useful Improvements in Pit-Silo-Wall Constructors, of which the following is a specification.

The present invention relates, generally, 10 to apparatus for applying plastic concrete to the walls of hollow, cylindrical building structures, and it proposes an improved apparatus of the class or character indicated which is especially designed for use in connection with underground silos. The apparatus in question is so constructed and arranged as to operate not only to apply the concrete to the wall of the silo, but also to complete the cutting of said wall prior to 20 the application of the concrete, to which end it contemplates the provision of an implement which serves both as a cutter or scraper and as a spreader, the implement being mounted upon a frame which revolves about 25 a fixed axis.

An embodiment of the invention is illustrated in the accompanying drawing, whereof,

Figures 1 and 2 are views in side elevation 30 and in plan, respectively, showing the apparatus in use;

Fig. 3 is an enlarged detail cross-section of the revolving frame, taken on line 3—3, Fig. 1;

35 Figs. 4 and 5 are enlarged detail sectional views of the plaster container and the aforementioned implement, carried by the said frame; and

Fig. 6 is an enlarged transverse section on 40 line 6—6, Fig. 1.

As previously stated, the improved apparatus constituting this invention is designed primarily for concreting the walls of underground silos such silos, as is generally known, being produced by digging a cylindrical hole in the ground and then applying plastic concrete to the wall of the hole. The greatest difficulty ordinarily experienced in the construction of a silo of the 45 character indicated resides in the formation of a truly perpendicular smooth concrete wall of substantially uniform thickness, for only such walls will possess the requisite resistance against caving in; but, on the other hand, the wall of the average excavated silo is not smooth, but full of depressions,

60 hollows and the like, and is seldom perpendicular to the surface of the ground and of uniform thickness. I propose to remedy these defects by constructing the present apparatus in such a way as to insure the production, under any and all conditions, of a silo having a truly-cylindrical, concrete-surfaced wall, the thickness of which is uniform throughout and may be varied at will. 65

Accordingly the procedure is substantially as follows:—A narrow hole 1 is first dug at a point which will be approximately central of the proposed silo, the hole having a depth, say, of twenty feet, and into this 70 hole is inserted the lower end of a rigid or inflexible, pole or mast 2 which is to subsequently form the fixed axis or pivot about which the hereinafter described frame 3 is adapted to swing. The said mast may be 75 constructed in any desired manner, so long as it is incapable of yielding, but it preferably consists of a vertical metal pipe 4 of the proper length and diameter, the interior of which contains a filling of hardened, or 80 set concrete 5, the mast end being secured in place in the bottom of the hole by means of a concrete filling 6 which is poured into said hole in a plastic state and then allowed to set. 85

The upper portion of the hole 1 is then enlarged for a depth of about six feet as indicated by the numeral 7, the diameter of such enlargement being slightly less than that desired for the silo. At the completion 90 of this operation, the revoluble frame 3 is connected to the pole and lowered until its bottom is just a little below the upper edge of the enlargement, the frame being intended to be utilized both in the scraping of the 95 wall of the enlargement and, also, in the application of the concrete thereto. As shown in Figs. 1 to 3, the said frame is of triangular shape, and preferably consists of a horizontal base board or bar 8, which is disposed flatwise and provided at its inner 100 end with an opening for the passage of the mast therethrough, a second horizontal bar 9 which is mounted upon bar 8 but is arranged edgewise instead of flatwise and is slightly shorter than the said bar 8, an upright bar 10 which is mounted upon the inner end of bar 8 and connected thereto and to the inner end of bar 9, and an inclined bar 11 which is connected at its upper 105 end to the upper end of bar 10 and at its lower end to the lower ends of bars 8 and 9. 110

These bars may be made of any desired material and the length of the bars 8 and 10 is approximately the same and is slightly less than the radius of the enlargement 7.

- 5 At its upper end, the frame is equipped with a suitable clasp or strap 12, adapted to engage the mast, so that tilting and similar movements are thus prevented.
- At its outer end, the bar 9 is provided 10 with an eye-bolt 13, or the like, to which is hinged the implement which is designed to effect either the scraping or the spreading operation, or both. For ordinary purposes, the same implement may be employed in both instances and may consist, 15 as here shown, of a trowel 14 which is arranged in a vertical plane and has one end sharpened or beveled. The angular adjustment of the trowel may be effected in any 20 desired manner as for instance, by means of a pair of threaded bolts 15, arranged at opposite sides of its hinge or pivot and rotatably mounted in threaded bearings 16 attached to the upper face of bar 8, the outer 25 ends of said bolts contacting with the trowel, as will be understood from Fig. 2. Consequently, by merely rotating the bolts in the proper direction, the trowel will be caused to swing about its hinge into the required position. Also the bolt 13 itself may be adjusted to move the trowel toward or from the 30 wall of the enlargement.

Mechanism of any suitable character may be provided for effecting the rotation of the 35 frame necessary to the cutting operation, or if preferred, such rotation may be produced manually, so that the said mechanism, even if employed, forms no part of the invention, wherefore illustration and description are omitted. Means or mechanism 40 is also provided for movably supporting the frame upon the mast in such a way as to permit it to be lowered gradually during both the cutting and the concreting operations, 45 and in the construction illustrated, a rope or other flexible element 17 is employed for this purpose, the frame being attached to one end of the rope and the latter then led over a pulley 18 at the top of the mast, its free end 50 being held by the operator.

It will be understood, therefore, from the foregoing that after the frame has been lowered into the enlarged portion 7 of the hole 1, and the trowel initially adjusted, the 55 frame is rotated, and after it has made a complete revolution it is again rotated, the steps specified being repeated until the bottom of the enlargement is reached. The frame is then raised, and the trowel adjusted to move its cutting edge slightly further outward, after which the rotation is again commenced, and in this way the wall of the enlargement is gradually shaved or scraped down until the required diameter 60 is obtained. The apparatus is then again

raised, and equipped with the concrete supplying device, the trowel being used to spread the concrete which is fed thereto in a wet or plastic state.

There may be employed as a container for 70 the concrete a hopper which is mounted upon the top of the frame at the opposite side of the mast from the trowel, so as to act, to some extent, as a counterweight. This hopper is provided with a discharge spout 75 opening into a screw conveyer 21 containing a screw 22 driven by suitable gearing 23, the casing of the screw opening into a downwardly-inclined pipe 24 that conveys the concrete to the trowel, to be spread by 80 the latter against the wall of the enlargement. When the trowel is to be utilized to apply the concrete, a segmental table 25 is preferably connected to the outer end of the frame bar 8, as shown, the curvature of the 85 outer edge of said table being substantially the same as that of the wall itself. The lower edge of the trowel is allowed to rest or nearly rest upon the upper face of the table, and the concrete is fed from the container to the space between the trowel and the wall, so as to be spread by the former during the rotation of the frame, the aforementioned pipe 24 preferably having its discharge end projecting through an opening 90 95 in the trowel.

The actual concreting operation is substantially similar in the main, to the cutting or scraping operation; that is to say, the supply of plastic concrete to the trowel is 100 started, and the frame rotated, the said frame being lowered after each complete revolution until the entire surface of the wall has been plastered with the cement. The thickness of the layer or coating of concrete 105 may be varied at will by adjusting the trowel in the proper manner, as will be understood, and since the wall has been gradually shaved down to the required size and the concrete applied gradually, the finished wall will be 110 of truly cylindrical shape at the conclusion of the operation, and its surface will be perfectly smooth and perpendicular to the bottom of the hole.

What I claim is:—

1. In a plastering machine, the combination with a vertical mast, of a horizontally rotatable frame mounted thereon, and provided with a spreading implement, a segmental table positioned upon said frame with 120 its resultant convex edge arranged to conform to the surface to which the plaster is to be applied, said spreading implement approximately resting upon said table, and means for supplying plaster to said spreading implement.

2. In a plastering machine, the combination of a horizontally rotatable frame, a tool hinged intermediate its ends to the outer end of said frame, and adjusting means ar- 130

ranged upon said table and positioned to engage said hinged tool upon opposite sides of its hinging point said adjusting means being longitudinally movable with respect to 5 the frame and upon opposite sides of said hinging point.

3. In a machine of the character described, the combination of a horizontally rotatable frame, a tool hinged intermediate its ends 10 to the outer end of said frame, adjusting members for engaging said tool, positioned upon said frame with respect to the hinge-

point of said tool and longitudinally movable with respect to said frame and upon opposite sides of said hinge-point, for effecting 15 the angular adjustment of said tool to the work to be operated upon, and a support whereon said frame is mounted.

In testimony whereof I affix my signature in presence of two witnesses.

RICHARD E. DILL.
